UNITED STATES PATENT OFFICE

EDWIN H. ALLFREE, OF IRONTON, OHIO

CONVEYER

Application filed December 10, 1927. Serial No. 239,110.

This invention relates to improvements in conveyers of the jiggling or shaker type for conveying loose or broken material, such as coal, ores, and the like, and comprising a conduit and an engine which imparts to the conduit a relatively short reciprocatory motion of such a character that material in the conduit will be moved along the same.

Objects of the invention are to provide an improved conveyer of the class referred to; to provide an improved driving engine or mechanism of an efficient nature adapted to be employed interchangeably at either side of the conveyer conduit without change in the relative height of the conveyer conduit and driving engine, which will provide for selecting the direction of conveyance at will, and which when located at either side of the conveyer conduit provides for readily reversing the direction of conveyance without change in the relative positions of the conveyer conduit and driving engine.

Another object of the invention is to provide in an improved driving engine possessing the characteristics referred to, for the attachment of the connection between the driving engine and the conveyer conduit at the under side of the conduit centrally of its sides when the driving engine is located at either side of the conveyer conduit.

A further object of the invention is to provide an improved driving engine of the character referred to which will be of simple, compact construction adapted to be easily assembled and connected with the conveyer conduit, and readily portable to meet the various changing conditions and demands encountered in the use of such conveyers in coal mines and for other purposes.

The invention, with other objects, novel features, and advantages thereof will be understood from the hereinafter contained detailed description, when considered in connection with the accompanying drawings, forming part hereof and illustrating one embodiment of the invention.

In the drawings:

Figure 1 is a top plan view of a conveyer constructed in accordance with the present

invention, the conveyer conduit being shown broken away.

Fig. 2 is a vertical section on the line 2—2 of Figure 1.

Fig. 3 is a detail horizontal section on the line 3—3 of Figure 2.

Fig. 4 is a detail top plan view of the engine driving arm.

Fig. 5 is a detail central longitudinal section of the engine driving arm.

Fig. 6 is a section on the line 6—6 of Figure 4.

Fig. 7 is a detail side elevation of a portion of the conveyer conduit.

Fig. 8 is a detail view of the conveyer conduit, a portion of the conduit being shown in transverse section and a part thereof in end elevation.

Fig. 9 is a detail central longitudinal section of the adjoining end portions of two of the trough sections of the conveyer conduit.

Figs. 10, 11, and 12 are diagrammatic views illustrating the progressive increase and lessening in velocity respectively of alternate strokes in the reciprocatory motion imparted to the conduit.

While a specific preferred embodiment of the invention is illustrated in the drawings, it will of course be understood that changes and variations may be made in the particular construction shown, and the invention embodied in other forms as will appeal to those skilled in the art and falling within the scope of the appended claims without departing from the spirit of the invention.

Referring to a detailed description of the particular embodiment of the invention illustrated in the drawings, the conveyer conduit or trough is shown as made up of a plurality of sections 1 detachably secured together. The ends of adjoining trough sections 1 are arranged in abutting relation, as shown, with the inner faces of the end portions of adjoining trough sections presenting with each other a smooth continuous surface so that the conveyer conduit is adapted to be operated to move material along the same in either direction, the trough sections being shown provided at the under side with bands 3 offset from the ends of the sections to form over-

lapping seats 3' for the ends of adjacent trough sections. Any suitable means may be employed for detachably securing the trough sections 1 together and for supporting the 5 same for reciprocatory movement. The coupling means for the sections shown in the drawings is of conventional form comprising bolts and nuts 4—5 engaging eyes or sleeves 6 on bands 7 secured to the under side of the 10 trough sections. The supporting means shown is also of well known standard construction comprising tracks 8 on the trough sections 1 cooperating with rollers 9 working in tracks 10.

15 The invention comprehends driving mechanism for imparting to the conveyer conduit reciprocatory motion wherein alternate strokes respectively progressively increase and diminish in velocity, together with means 20 for reversing the direction of the alternate accelerated and retarded strokes in the reciprocatory movement whereby the direction of conveyance of material along the conveyer conduit may be changed. Referring in detail 25 to the particular embodiment of the driving mechanism shown in the drawings, 11 designates a suitable support or stand, the same being shown as comprising a base made up of side longitudinal steel channel members 12,

30 13, a transversely extending plate 14 and transverse members 15, 16, suitably secured together. 17 designates a housing section or plate supported upon and suitably secured to the longitudinal side members 12, said housing section being disposed above the plate member 14. Upon the housing section or plate 17 is an upper housing section 18 secured thereto by bolts and nuts 19, 20. Mounted upon the support or stand 11 at one end thereof 35 to one side of the housing sections 17, 18 is an electric motor 21. 22 designates a horizontally extending worm shaft supported in suitable bearings 23, 24 in the upper housing section 18, said worm shaft being disposed at one end of said housing section and having an end portion 22^a extending outside thereof and connected with the shaft 25 of the motor 21. On the end portion 22^a of the worm shaft 22 is fixed a fly wheel 26. The worm shaft 22 is connected with the motor shaft 25 by a sleeve 27 fitting over and suitably keyed to the latter and provided with a flange 28 that fits against one side of the fly wheel 26 and is secured thereto by bolts 29. Meshing with the worm shaft 22 is a worm wheel 31, which is fixed on a vertical shaft 30 within the upper housing section 18, said shaft being supported in suitable anti-friction bearings 32, 33, on the housing sections 17, 18. The lower bearing 32 for the vertical shaft 30 is shown supported by a tubular member or ring 34 that fits in adjoining openings in the housing sections 17, 18, and has a flange 35 interposed between said housing sections and secured thereto by bolts and nuts 36, 37. On the

lower end of the vertical shaft 30 disposed within the space between the bottom plate 14 and the housing section 17 is a crank 38. The upper housing section 18 is adapted to hold lubricant for the worm gearing 22, 31, and the bearings therein and arranged within said housing section is a tubular member 39 surrounding the vertical shaft 30 and serving as an oil baffle, the normal level of the oil in said housing section being below the top 70 of said tubular member. The tubular member 39 is secured by screws 40 upon the supporting ring 34, and said tubular member engages over and holds in place the lower bearing 32 of the vertical shaft 30. 41 designates a sight feed lubricator of conventional form mounted upon the upper housing section 18 for supplying lubricant to the pin 38^a of the crank 38, the vertical shaft 30 being provided with an interior channel 42 leading to the pin 38^a of the crank 38 and connected with the lubricator 41.

Disposed longitudinally of the support or stand 11 at the lower part thereof and supported at one end thereon for horizontal oscillatory movement is a drive arm 43, which is connected intermediate its ends with the crank 38 by a rod 44, said rod engaging a pin 45 on said drive arm. The drive arm 43, in the present instance, is shown made up of a frame 46 and upper and lower plates 47, 48, riveted thereto, the arm being widest at a point between and tapering toward its ends. At one end the drive arm 43 has an eye or bearing 49 engaging a pivot pin 50 on one end of the support or stand 11. The other end of the drive arm 43 projects beyond one end of the support or stand 11, as shown, and is connected with the conveyer conduit 1 at the under side thereof centrally of its sides so that rectilinear movement will be imparted to the conveyer conduit by the drive arm. The connection between the drive arm 43 and the conveyer conduit 1 is shown as comprising a link 51 having a vertical conveyer connection 52 at one end with the conveyer conduit 1. At its other end the link 51 has a vertical pivotal connection 53 with a clevis member 54 which in turn has a horizontal pivotal connection with the drive arm 43, said drive arm having a bearing 43^a engaging a vertical pivot bolt 55 of the clevis member 54.

The driving mechanism hereinbefore described operates as follows:

The motor 21 rotates the vertical crank shaft 30 through the worm shaft 22 and worm wheel 31 at reduced speed, the crank 38 being accordingly rotated at relatively slow speed. The relatively slow rotary motion of the crank 38 is converted, through the rod 44, into the desired reciprocatory motion and transmitted to the drive arm 43, which imparts the same through the link and clevis connections 51—54, to the conveyer conduit 1, the conveyer conduit being reciprocated 120 125 130

rectilinearly. In the reciprocatory motion imparted to the driving arm 43 and the conveyer conduit 1, alternate strokes respectively progressively increase and diminish in velocity, the angular effect of the relatively short connecting rod 44 modifying or changing the harmonic rotary motion of the crank 38 at one end of the connecting rod 44 into the desired accelerated and retarded reciprocatory movement at the other end of said connecting rod 44. The relative velocities of the forward and reverse strokes of the reciprocatory motion imparted to the conveyer conduit 1 by the driving mechanism are indicated by the velocity diagram in Figure 10. Starting slowly at A, the conveyer conduit 1 travels forward as indicated by the arrow in the direction of conveyance, with slowly increasing velocity through the greater part of the stroke, reaching the maximum at a point near the end of the stroke indicated in the diagram at M, after which it rapidly declines to the minimum as the conveyer conduit 1 comes to a relatively sudden stop at the point designated B. On the return stroke the conveyer conduit 1 starts rapidly in the opposite direction and rapidly increases in velocity until the maximum is reached early in the stroke at a point indicated at m in the diagram. From then on throughout the remaining greater portion of the stroke it slowly declines in velocity to the minimum and comes to a relatively gradual stop at the point designated A.

As will be understood during each revolution of the crank the sequence of change in velocity of the reciprocating member is, slow increase, rapid decline (during the forward stroke in the direction of conveyance) and rapid increase, slow decline, (during the return stroke). It will be noted that maximum acceleration occurs toward the end of the forward stroke and toward the beginning of the return stroke, the velocity sequence for the return stroke being exactly the reverse or the opposite of the velocity sequence of the stroke forward in the direction of conveyance, the period of time or velocity of each stroke, as a whole, being the same.

The angular effect of the relative short connecting rod 44 in changing the regular rotary motion of the crank 38 into the accelerated and retarded reciprocatory motion as hereinbefore explained is illustrated diagrammatically in Figures 11 and 12 of the drawings. Referring particularly to Figure 11 it will be noted that the stroke of the crank H equals the distance between the points A—B; that the stroke of the link L equals the distance C—D; the distance between the points A—B equals the distance C—D, and C—F equals the distance between the points designated F—D. The distance 65 between the points A—E, however, is more

than the distance E—B, and therefore while the distance C—F equals the distance F—D, the speed at C—F is less than F—D.

By changing the relative location of the pin 45 on the drive arm 43 to the position at the other side of the drive arm indicated by dotted lines in Figure 4 of the drawings, which dotted line position is substantially 180° from the position of the pin 45 illustrated in full lines, the effect of the angularity of the crank 38 will be reversed, and the direction of the alternate accelerated and retarded strokes, and the direction of conveyance will be reversed. In the particular exemplification of the invention illustrated in the drawings, in order to provide for changing the location of the pin 45 on the drive arm 43 and the relative angularity of the rod 44 to reverse the direction of the alternate accelerated and retarded strokes, and the direction of conveyance, said pin 45 is fixed on a disk 56 which is mounted for rotary adjustment on the drive arm 43. The disk 56 is provided with a peripheral flange 57 and with an open central bearing or hub 58. The disk 56 is arranged between the plates 47, 48, of the drive arm 43. It is supported for rotary adjustment by said plates and also by a central stud 59 secured to the bottom plate 47 by bolts and nuts 60, 61, said stud engaging the central bearing or hub 58 of the disk 56 and having a flange 61 engaging over the upper side of said bearing or hub. The disk 56 is provided with a toothed portion 62 extending substantially over half of its periphery and 63 is a pinion supported for rotation on the driving arm between the plates 47, 48, and meshing with the toothed peripheral portion 62 of the disk 56 for turning the same to its different positions of adjustment, said pinion being adapted to be operated by a spindle 64 to which the pinion is fixed and which is provided with an angular faced head, as shown, to be engaged by a wrench or other tool suitable for the purpose. Means is provided for locking the disk 56 in its different positions of adjustment. The disk 56 is provided with apertures 66—66' located near the periphery thereof at diametrically opposite points. Aligned apertures 67 and 68 are provided in the plates 47 and 48, and 65 is a bolt adapted to be engaged with said last mentioned apertures and either one of the apertures 66—66' in the disk 56 to lock the disk in its different positions of adjustment. In Figure 4 of the drawings, the locking bolt 65 is shown engaging the apertures 66 of the disk 56. As will be readily understood, all that is required to change the direction of conveyance, is to remove the locking bolt 65, rotate the disk 56 by the pinion 63 through substantially 180° until the other aperture 66' of said disk is in alignment with the apertures 67, 68 of the plates 47, 48, and

then lock the disk 56 in position by engaging the bolt 65 with the apertures 67—68 and the apertures 66'.

70 and 71 designate stop portions on the upper plate 47 adapted to be engaged by the collar portion 69 of the pin 45 to limit the rotary movement of the disk 56 in turning the same to its different positions of adjustment.

70 It will be noted that the particular construction of conveyer hereinbefore set forth possesses the following important novel characteristics.

First: It is either right or left hand, that is, with any given lay out of the conveyer conduit and direction of conveyance, the driving engine or mechanism may be placed on either side of the conveyer conduit without any change in the relative height of the conveyer conduit and driving engine.

Second: The direction of conveyance may be selected at will. With any given lay out of conveyer conduit and with the driving engine located to either the right or left hand side of the conveyer conduit, the direction of conveyance may be reversed without changing the location of the driving engine, without any change in the arrangement or elevation of the conveyer conduit, and without even disconnecting the drive rod connections between the driving engine and the conveyer conduit.

Third: The connection from the driving engine to the conveyer conduit is under slung and centrally attached at all times, whether the driving engine is located on one side or the other and regardless of the direction of conveyance.

Fourth: The improved driving mechanism is of simple, compact construction adapted to be easily connected with the conduit and readily portable.

What I claim is:

1. A conveyer comprising a conduit supported for reciprocatory movement, and an engine for imparting to the conduit reciprocatory motion wherein slowly accelerated but rapidly retarded advance alternates with rapidly accelerated but slowly retarded return, and means entirely in said engine for reversing the direction of said advance and return in the reciprocatory movement providing for the operation of the conveyer to move material along the same in either direction.

2. A conveyer comprising a conduit supported for reciprocatory motion, and an engine for imparting to the conduit reciprocatory motion wherein slowly accelerated but rapidly retarded advance alternates with rapidly accelerated but slowly retarded return, a drive connection between the engine and the conduit at the under side thereof, and means entirely in said engine for reversing the direction of the alternate advance and re-

turn in the reciprocatory movement providing for the operation of the conveyer to move material along the same in either direction.

3. A conveyer including a conduit supported for reciprocatory movement, and operating means for imparting to the conduit reciprocatory motion wherein slowly accelerated but rapidly retarded advance alternates with rapidly accelerated but slowly retarded return, said operating means comprising a rotating crank, a reciprocating member, and a rod connection between the crank and said reciprocating member, and means for reversing the angularity of said connecting rod relatively to said crank and reciprocating member to reverse the direction of the alternate advance and return of the reciprocating member providing for the operation of the conduit to move material along the same in either direction.

4. A conveyer including a conduit supported for reciprocatory movement, and operating means for imparting to the conduit reciprocatory motion wherein slowly accelerated but rapidly retarded advance alternates with rapidly accelerated but slowly retarded return, said operating means comprising a rotating crank, an arm pivotally supported at one end for oscillation, a connection between the other end of said arm and the conduit, a rod connection between the crank and said arm intermediate its ends whereby the arm is oscillated by the crank, and means for reversing the angularity of said rod relatively to the crank and the arm to reverse the direction of the alternate advance and return in the reciprocatory motion imparted to the conduit.

5. A conveyer including a conduit supported for reciprocatory movement, and operating means for imparting to the conduit reciprocatory motion wherein slowly accelerated but rapidly retarded advance alternates with rapidly accelerated but slowly retarded return, said operating means comprising a rotating crank, an arm pivotally supported at one end for oscillation, a connection between the other end of said arm and the conduit, a pin on said arm, and a rod connection between said pin and said crank whereby the arm is oscillated by the crank, said pin being adjustably mounted on the arm to provide for reversing the angularity of the rod relatively to the crank and the arm to reverse the alternate advance and return in the reciprocating movement imparted to the arm.

6. A conveyer including a conduit supported for reciprocatory movement, and operating means for imparting to the conduit reciprocatory motion wherein slowly accelerated but rapidly retarded advance alternates with rapidly accelerated but slowly retarded return, said operating means comprising a rotating crank, an arm pivotally supported at one end for oscillation, a connection between

- the other end of said arm and the conduit, a rod connection between the crank and said arm intermediate its ends whereby the arm is oscillated by the crank, and means for reversing the angularity of said rod relatively to the crank and the arm to reverse the direction of the alternate advance and return in the reciprocatory motion imparted to the conduit, said last mentioned means comprising a disk mounted upon said arm for rotary adjustment, means for locking the disk to the arm in different positions of adjustment relatively thereto, and a pin on said disk to which the rod is connected. 5
- 15 7. A conveyer including a conduit supported for reciprocatory movement, and operating means for imparting to the conduit reciprocatory motion wherein slowly accelerated but rapidly retarded advance alternates with rapidly accelerated but slowly retarded return, said operating means comprising a rotating crank, an arm pivotally supported at one end for oscillation, a connection between the other end of said arm and the conduit, a rod connection between the crank and said arm intermediate its ends whereby the arm is oscillated by the crank, and means for reversing the angularity of said rod relatively to the crank and the arm 20 to reverse the direction of the alternate advance and return in the reciprocatory motion imparted to the conduit, said last mentioned means comprising a disk mounted upon said arm for rotary adjustment and having a toothed peripheral portion, a toothed member on the arm meshing with the toothed peripheral portion of said disk, means for actuating said toothed member to adjust said disk, and means for locking the disk to the 25 arm in different positions of adjustment relatively thereto. 40
8. A conveyer including a conduit supported for reciprocatory movement, and operating means for imparting to the conduit reciprocatory motion wherein slowly accelerated but rapidly retarded advance alternates with rapidly accelerated but slowly retarded return, said operating means comprising a rotating crank, an arm pivotally supported at one end and operatively connected intermediate its ends with said crank to be oscillated thereby, an operative connection between the other end of said arm and the conduit, and means for reversing the direction of the advance and return in the reciprocatory movement of said arm providing for operation of the conduit to move material along the same in either direction. 45
- 50 9. A conveyer including a conduit supported for reciprocatory movement, and operating means for imparting to the conduit reciprocatory motion, said operating means comprising a connecting rod to one end of which is imparted continuous uniform rotary motion that is converted at the 55 other end of the rod to reciprocatory movement wherein the advance is slowly accelerated but rapidly retarded and the return is rapidly accelerated but slowly retarded respectively relative to the linear velocity of the rotating end of the rod, and means for reversing the direction of said advance and return movements of the said connecting rod. 70
10. A conveyer including a conduit supported for reciprocatory movement, operating means for imparting to the conduit reciprocatory motion, said operating means comprising a rotating driving member and a reciprocatory follower member, each with fixed paths of movement, the reciprocatory follower member having slowly accelerated but rapidly retarded advance alternating with rapidly accelerated but slowly retarded return respectively relative to the linear velocity of the rotating driving member, and means for reversing the direction of said advance and return of the said follower member. 75
11. A conveyer including a conduit supported for reciprocatory movement, and operating means for imparting to the conduit reciprocatory motion, said operating means comprising a pivotally supported oscillating member operatively connected to the conduit, a rotating crank operatively connected with the oscillating member to oscillate the same with slowly accelerated but rapidly retarded advance strokes alternating with rapidly accelerated but slowly retarded strokes respectively relative to the linear velocity of the crank, and means for reversing the direction of the said advance and return strokes imparted to the oscillating member. 80
12. A conveyer including a conduit supported for reciprocatory movement, and operating means for imparting to the conduit reciprocatory motion wherein slowly accelerated but rapidly retarded advance alternates with rapidly accelerated but slowly retarded return, said operating means comprising a support, a drive arm pivotally mounted at one end on the support for horizontal oscillatory movement and operatively connected at its other end with the conduit, a vertically extending shaft mounted for rotation on the support, a crank on the lower part of said shaft operatively connected with said drive arm for oscillating the same, and means for reversing the direction of the advance and return strokes in the reciprocation of said drive arm providing for the operation of the conduit to move material along the same in either direction. 85
13. A conveyer including a conduit supported for reciprocatory movement, and operating means for imparting to the conduit reciprocatory motion wherein slowly accelerated but rapidly retarded advance alternates with rapidly accelerated but slowly retarded return, said operating means com- 90
- 105

prising a support, a drive arm pivotally mounted at one end on the support for horizontal oscillatory movement and operatively connected at its other end with the conduit, 5 a vertically extending rotary shaft mounted on the support, a crank on the lower part of said shaft, a rod connection between the crank and the drive arm whereby the arm is oscillated by said crank, and means for reversing the angularity of said rod relatively to the crank and the arm to reverse the direction of the alternate advance and return strokes imparted to the drive arm.

14. A conveyer including a conduit supported for reciprocatory movement, and operating means for imparting to the conduit reciprocatory motion wherein slowly accelerated but rapidly retarded advance alternates with rapidly accelerated but slowly retarded return, said operating means comprising a support, a drive arm pivotally mounted at one end on the support for horizontal oscillatory movement and operatively connected at its other end with the conduit, a vertically 20 extending rotary shaft on the support, a crank on the lower part of said shaft, a rod connection between the crank and drive arm whereby the arm is oscillated by the crank, said rod connection including a pin on the 25 drive arm to which said rod is connected, said pin being adjustable on said drive arm to change the angularity of said rod relatively to the drive arm and crank to reverse the advance and return strokes in the reciprocation 30 of the drive arm.

15. A conveyer including a conduit supported for reciprocatory movement, and operating means for imparting reciprocatory motion to the conduit, said means comprising 40 a support, an electric motor on said support, a horizontally extending rotary worm shaft on the support coupled with the shaft of the motor, a vertically extending rotary shaft on the support, a worm wheel fixed on the vertical shaft and meshing with said worm shaft, a crank on the lower part of the vertical shaft, an arm pivotally supported at one end on the support for horizontal oscillatory movement and operatively connected at its other end 45 with the conduit, and a rod connection between said crank and arm intermediate its ends.

16. A conveyer including a conduit supported for reciprocatory movement, and operating means including a stand having upper and lower housing sections at one end thereof, a motor mounted on the stand at one side of said housing sections, a horizontally extending rotary worm shaft disposed within 55 the upper housing section and coupled to the shaft of the motor, a vertical rotary shaft extending through the upper housing section, a worm wheel within the upper housing fixed on the vertical shaft and meshing with the 60 worm shaft, a crank on the lower part of the 65

vertical shaft disposed within the lower housing section, a horizontally disposed drive arm pivotally supported at one end of the stand at the lower part thereof for oscillation and operatively connected with said crank, and a connection between the other end of the drive arm and the conduit.

17. A conveyer including a conduit supported for reciprocatory movement, and operating means including a stand having at one end a housing disposed above the base thereof, a motor on the stand at one side of said housing, a horizontally extending worm shaft disposed within the housing and coupled with the shaft of the motor, a vertical shaft extending through the housing to the under side thereof, a worm wheel within the housing fixed on the vertical shaft and meshing with said worm shaft, a crank on the lower end of the vertical shaft, a drive arm pivotally supported at one end on the lower part of the stand and operatively connected with said crank; and a connection between the other end of the drive arm and the conduit, said shaft being provided with a lubricating channel leading from its upper end to the said crank, and a lubricator mounted on the top of the housing and connected with said channel.

18. A conveyer including a conduit supported for reciprocatory movement, and operating means including a stand having at one end a housing disposed above the base thereof, a motor on the stand at one side of said housing, a horizontally extending worm shaft disposed within the housing and coupled with the shaft of the motor, a vertical shaft extending through the housing to the under side thereof, a worm wheel within the housing fixed on the vertical shaft and meshing with said worm shaft, a crank on the lower end of the vertical shaft, a drive arm pivotally supported at one end on the lower part of the stand and operatively connected with said crank, and a connection between the other end of the drive arm and the conduit, means for supplying lubricant to said housing, and a tubular member within the housing surrounding the vertical shaft and serving as means for retaining lubricant within said housing.

In testimony whereof I hereunto affix my signature.

EDWIN H. ALLFREE.
